UNITED STATES PATENT OFFICE.

JAMES ARMSTRONG ERWIN, OF ATLANTA, GEORGIA.

SHIRT AND TROUSERS SUPPORT.

1,110,912.

Specification of Letters Patent.

Patented Sept. 15, 1914.

Application filed December 23, 1912. Serial No. 738,198.

To all whom it may concern:

Be it known that I, JAMES ARMSTRONG ERWIN, a citizen of the United States, and a resident of Atlanta, in the county of Fulton and State of Georgia, have invented a new and Improved Shirt and Trousers Support, of which the following is a full, clear, and exact description.

The object of the invention is to provide a new and improved shirt and trouser support, arranged to hold the shirt down and the trousers up without undue strain on the wearer's body, at the same time giving the desired comfort and allowing free movement of the arms, shoulders and upper portions of the wearer's body.

In order to accomplish the desired result, use is made of front and rear straps attached to and depending from the yoke of the shirt at the inside thereof, the lower ends of the straps terminating approximately adjacent the hip portions and being secured to the shirt body, the said terminals and the said shirt body being provided with registering buttonholes for engagement by detachable buttons projecting to the outside of the shirt, and keepers attached to the inner face of the waistband of the trousers and adapted to be engaged by the projecting ends of the said buttons.

A practical embodiment of the invention is represented in the accompanying drawings forming a part of this specification, in which similar characters of reference indicate corresponding parts in all the views.

Figure 1 is a front elevation of the shirt and trouser support as applied, part of the shirt body being shown broken out and the trousers being shown partly open; Fig. 2 is a rear elevation of the shirt as applied, part of the back of the shirt being broken out; Fig. 3 is a side elevation of the same; Fig. 4 is an enlarged sectional plan view of the shirt and trouser support on the line 4—4 of Fig. 1; Fig. 5 is a transverse section of the shirt on the line 5—5 of Fig. 1; Fig. 6 is an enlarged face view of one of the keepers on the trousers; and Fig. 7 is a similar view of a modified form of the same.

The shirt A is of the usual construction and provided with a body A', sleeves A² and a yoke A³, and to the yoke A³ are sewed or otherwise fastened the upper ends of front and rear straps B, B and C, C depending from the said yoke at the inside of the

body A' of the shirt A. The lower ends B', B' and C', C' of the front and rear straps B, B and C, C are somewhat widened and are fastened by rows of stitches D and D' to the body A' of the shirt A so that the straps B, B and C, C are free from the body A intermediate the yoke A³ and the widened portions B' and C'. The widened portions B' and C' of the front and rear straps B and C are provided with sets of spaced buttonholes E and E' extending through the body A' of the shirt at the front and rear thereof, and the said buttonholes E and E' are adapted to be engaged by detachable buttons F, F' similar to collar buttons and extending to the outside of the shirt to be engaged with keepers G, G' secured to the inside of the waistband H' of the trousers H so as to support the latter. The keepers G, G' are arranged in spaced relation to the corresponding buttons F, F' so as to permit of conveniently engaging the outer heads of the buttons with the said keepers to properly hold up the trousers H. Each of the keepers G, G' is preferably made from sheet metal or similar sheet material and is provided with two or more retainers G² arranged one above the other so as to hold the trousers up more or less according to which of the retainers G² is engaged by the corresponding button. For holding the trousers up higher the buttons are engaged with the lower retainers and for lowering the trousers the buttons are engaged with the upper retainers. However, each keeper may be made single, as indicated in Fig. 7.

It is understood that each retainer is provided with an enlarged opening for the passage of the outer head of the button and a narrow passage for the shank of the button to permit of conveniently engaging the corresponding button with or disengaging the same from the corresponding keeper.

From the foregoing it will be seen that the straps B and C form permanent parts of the shirt A, and in using the shirt and the trouser support it is only necessary for the user to insert the buttons F, F' in the buttonholes E, E' and to engage the outer ends of the said buttons with the corresponding keepers G, G'.

It will be noticed that by the arrangement described the shirt A is held down while the trousers are properly supported, and

practically the entire weight is sustained from the shoulders owing to the connection of the straps B and C with the yoke A³ of the shirt A. By having the straps B and C detached from the body A' of the shirt between the ends of the said straps, it is evident that the shirt especially the bosom or the front thereof hangs properly and is not interfered with in the least by the straps.

10 The shirt and trousers support shown and described is very simple in construction and can be cheaply manufactured.

Having thus described my invention, I claim as new and desire to secure by Letters Patent:

15 A shirt comprising a body having a yoke, front and rear straps permanently secured at their upper ends to the front and rear of

the yoke at the shoulders, the said front and rear straps extending freely from the yoke 20 at the inside of the shirt for the greater portion of their length and having their lower ends widened and permanently fastened to the inner side of the shirt body by stitches, and the widened portions of the 25 straps being provided adjacent opposite sides with upper and lower button-holes which also extend through the shirt body, all for the purpose described.

In testimony whereof I have signed my 30 name to this specification in the presence of two subscribing witnesses.

JAMES ARMSTRONG ERWIN.
